UNITED STATES PATENT OFFICE.

JACKSON L. POSTON, OF WIEHLE, VIRGINIA.

SHINGLE-SAWING MACHINE.

SPECIFICATION forming part of Letters Patent No. 769,019, dated August 30, 1904.

Application filed November 7, 1903. Serial No. 180,248. (No model.)

To all whom it may concern:

Be it known that I, JACKSON L. POSTON, a citizen of the United States, residing at Wiehle, in the county of Fairfax and State of Virginia, have invented new and useful Improvements 5 in Shingle-Sawing Machines, of which the following is a specification.

This invention relates to shingle-sawing machines, and has for its object to provide in 10 such a machine a rotatable gage-block adapted to alternately present the bolt or block from which the shingles are to be sawed to the saw in such manner that the shingles will be alternately sawed from heel to toe and from toe to heel, whereby the entire bolt will be utilized 15 without waste—that is to say, one shingle will be cut from its thick to its thin end and the next shingle from its thin to its thick end.

It also has for its object to provide automatic mechanism for releasing the sawed shingle to permit it to drop from the machine and also to provide improved means for automatically restoring the gage mechanism to its normal condition when the carriage has been re- 25 tracted preparatory to sawing another shingle.

It has for a further object to provide improved means for adjusting the releasing mechanism in order to release the shingles at different periods during the travel of the carriage to adapt the machine to sawing shingles 30 of different lengths.

It also has other objects in view, which will fully hereinafter be made apparent.

To these ends my invention consists in the 35 features and in the construction, combination, and arrangement of parts hereinafter described, and particularly pointed out in the claims following the description, reference being had to the accompanying drawings, forming a part of this specification, wherein—

Figure 1 is a side elevation. Fig. 2 is a top plan view. Fig. 3 is an end elevation. Figs. 4, 5, 6, and 8 are detail sectional views, and Fig. 7 is a detail view of the gage-block.

The numeral 1 indicates the bed of the machine comprising two longitudinal side rails 2 and two cross-beams 3 between the ends of the side rails, said bed being supported on suitable uprights 4. Mounted on the bed are 45 parallel stringers 5, on which are mounted

rails 6 and 7. Fixed to one end of the bed are two transverse parallel beams 8, which are extended on one side of the machine, as shown, and on the extended edge of said beams is a stringer 9, on which is mounted a rail 10. 55 Journaled in suitable bearings 11, attached to the other side of the bed 1, is a shaft 12, on one end of which is fixed a circular saw 13. On the other end of said shaft is fixed a band-pulley 14 for driving the saw-shaft. Fixed on 60 the bed to one side of the stringers 5 is a work-holding table 15 for holding a quantity of bolts or blocks from which the shingles are to be cut. Fixed transversely on the extensions of the beams 8 is a board 16, which is set up 65 on edge, as shown, one side of which is in alinement with the circular saw, the end of the board adjacent to the saw being beveled, as at 17, to permit the end of said board to extend slightly beyond the edge of the saw 70 for the purpose hereinafter made apparent.

The numeral 18 indicates a carriage comprising a table 19, which is provided with rollers 20, arranged to travel on the rails 6 and 7. Fixed on one end of the table are two 75 cross-beams 21 and 22, which extend at one end laterally beyond the table, the cross-beam 22 extending farther from the table than the cross-beam 21. Fixed to the under side of the cross-beam 22 are hangers 23, one on each side, one only being shown in the drawings, in which is journaled a roller 24, which is adapted to travel on the rail 10. Mounted upon one of the side rails 2 of the bed is a bearing-block 25, in which is journaled a roller 80 85 26, which is in frictional engagement with the under side of the work-table 15 and aids in supporting said work-table.

Supported on the cross-beams 21 and 22 is a beam or arm 27, which is normally parallel 90 to the work-table and to the circular saw. The beam or arm 27 is pivoted at one end, as at 27^a, to the cross-beam 21 and at its other end loosely rests and is adapted to slide on the extended end of the beam 22. A stop 27^b 95 is rigidly fixed to the upper side of the cross-beam 22 and limits the movement of said beam or arm 27 in a direction toward the table.

Fixed transversely to the beam 27 are two cross-bars 28. Each of said cross-bars is lon- 100

itudinally slotted, as at 29, and passing through said slots and through the stringer are bolts 30. By loosening the bolts the cross-bars 28 may be adjusted transversely to the beam 27, and after the desired adjustment is effected said cross-bars may be rigidly secured in place by tightening up said bolts. Formed in one end of each of the cross-bars 28 is a bearing 31, and journaled in said bearings is a shaft 32, on which is rigidly fixed a gage-block 33. Said gage-block is provided with two reversely-inclined sides 34 and 35, said inclined sides of the gage-block being arranged at slight angles to the plane of the saw. Fixed on the shaft 32 is a stop for limiting the rotary movement of the shaft and gage-block, said stop comprising a disk 36, having formed thereon two shoulders 37 and 38, and fixed on the opposite sides of the beam 27 are two spring-pawls 39 and 40, said pawls consisting of flat springs, which are each slotted at one end, and passing through said slots are screws or bolts 41 to permit of the lengthwise adjustment of said pawls for the purpose hereinafter to be made apparent. The free ends of the pawls 39 and 40 rest on the opposite sides of the periphery of the disk 36, and the shoulders 37 on said disk are formed at such distances apart that they will alternately be engaged by one or the other of said pawls, as the shaft 32, carrying the gage-block, is alternately rotated one-quarter of a revolution in alternate directions. The pawls 39 are secured to the upper and lower sides of the arm 27 by screws or bolts 41, which pass through the elongated slots in said pawls and into the said arm, whereby the said pawls may be adjusted lengthwise on the said arm for the purpose hereinafter set forth. The end of the shaft 32 on which the disk is fixed is extended slightly beyond the end of the carriage and is there provided with a crank 42, by means of which the shaft may be alternately partially rotated in opposite directions.

Attached to the free end of the arm 27 is one end of a coiled spring 43, the other end of which is attached to the extension of the cross-beam 22, said spring exerting a constant force tending to draw the free end of said arm in a direction away from the table. Pivoted to said extended arm of the cross-beam 22 is a trigger 44, one end of which is rabbeted to form a shoulder 45 to engage the free end of the arm 27 and hold said arm in parallelism with the table. The opposite end of the trigger is provided with a pendent arm 46. The shouldered end of the trigger is held in engagement with the side of the arm 27 by means of a flat spring 47, which is fixed at one end to the under side of the extended end of the cross-beam 22 and at its free end bears against the under side of a pin 48, fixed in one side of the shoulder end of the trigger, said spring having a constant tendency to hold the shouldered end of the trigger elevated and in en-

gagement with the side or edge of the pivoted arm 27.

Fixed to the under side of the table, as before described, are two cross-beams 8, one end of each of which is extended away from the bed of the machine, and to one end of the said cross-beam is bolted one end of an arm 51.

The arm 51 is slotted, as at 52, and through said slot passes the attaching-bolt 53, whereby said arm may be adjusted lengthwise. The outer side of the arm 51 is beveled or inclined, as shown, and to said latter inclined side of the arm is attached a cam 54, the arrangement being such that as the carriage moves forward to saw a shingle the pendent arm 46 of the trigger will engage the cam 54, and as the carriage continues to move forward said cam will throw the pendent arm outward, depressing the shouldered end of the trigger until it finally causes said shouldered end to disengage the pivoted arm, whereupon the coiled spring 43 will immediately contract and draw the free end of said pivoted arm away from the table.

Fixed on the two cross-beams 8 are two uprights 55, on the upper ends of which is rigidly secured a flat plate 56, the inner edge of which is curved, as at 57, said curved edge gradually approaching the carriage toward its rear end, as shown. The plate 56 may conveniently consist of a flat piece of wood and in such case will be provided with a wear-plate 58, formed of any suitable metal. Pendent from the pivoted arm 27 is a vertical rod or shaft 59, on the lower end of which is journaled a roller 60, which is adapted when the swinging arm has been released by the trigger to travel in contact with the wear-plate 58, the arrangement being such that after the pivoted arm has been released by the trigger and the carriage is retracted said roller will travel in contact with said wear-plate, and owing to the curvature of the latter the roller, together with the pivoted arm, will be forced inwardly toward the table, and thus will restore the arm to its normal position, immediately upon which the spring 47 will elevate the free end of the trigger and cause the shoulder 45 to engage the side of the pivoted arm and hold the latter in its normal position.

Fixed on the inner side of the work-table 15 is a pin 61, and fixed on the adjacent side of the table is a forwardly-projecting pin 62, said pins being arranged at such relative distances apart that when the table is moved sufficiently far forward to saw the shingle the pin 62 will engage the pin 61 and prevent any further forward movement of the table. The movement of the table in the reverse direction is limited by the roller 60 impinging against the end of the wear-plate 58 when the pivoted arm has arrived at its normal position, it being obvious that after this has occurred the roller which is carried by said swinging arm can move no farther toward the carriage.

Hence the carriage can be moved no farther rearward. Fixed to the upper side of the rear end of the table is a transverse cleat 63, which serves as an abutment for one end of the bolt 5 or block from which the shingles are to be sawed.

The operation of my improved machine is as follows: The bolt or block from which the shingles are to be sawed is placed on the table with its rear end resting against one of the inclined sides—as 34, for example—of the gage-block 33. The bolt will thus be presented at an angle to the saw. The carriage is now moved forward either by hand or by any suitable mechanism 15 which may be provided for the purpose, and as it moves forward it will present the bolt to the saw in such manner that the latter will saw a shingle from one side of the bolt, and in the example herein given the saw operates 20 to first saw the thick end of the shingle, and as the carriage moves forward the saw will operate to cut nearer and nearer to the edge of the bolt, thus producing a shingle thick at one end and gradually tapering toward its 25 other end. Toward the end of the movement of the carriage the pendent arm 26 of the trigger will engage the cam 54, and as the carriage continues to move forward said pendent arm will move outwardly, and thus depress the 30 shouldered end of the trigger, and when the carriage has been moved sufficiently far forward to completely saw the shingle from the bolt said pendent arm will have been moved sufficiently far outward to cause the shoulder on 35 the end of the trigger to disengage the free end of the pivoted arm 27, whereupon the coiled spring 43 will draw the said free end of the arm away from the carriage, thus releasing the shingle and permitting the latter to drop from the machine. As the carriage 40 is moved forward to saw the shingle the shingle as it is cut from the bolt rests upon the upper edge of the board 16, which latter acts as a support for the shingle until the latter has 45 been completely severed and is dropped in the manner described. After the shingle has been sawed and dropped the carriage is retracted, and in its retractile movement the roller 60 travels in contact with the wear-plate 58 and 50 moves the pivoted arm toward the table until the free end of the pivoted arm abuts the stop, and when this occurs the shouldered end of the trigger will be elevated by the spring 47, and the shoulder will engage the side of the pivoted 55 arm and hold the latter in its normal position. The shaft 32 is now given the quarter-turn by means of the crank 42 and presents the reversely-inclined side 35 of the gage-block 33. The bolt is now moved up against said side 60 of the gage-block, thus presenting said bolt to the saw in a reverse angular direction to that before described. The carriage is again moved forward to cause the saw to engage the bolt, and the saw will now operate to commence at the thin end of the shingle to be 65

sawed, and as the bolt moves forward with the carriage the saw will cut gradually farther and farther away from the edge of the bolt, thus sawing from the thin edge of the shingle to the thick edge. The above-described operation is repeated until the entire bolt has been sawed up into shingles, the saw operating through the medium of the mechanism described to alternately cut through the edges of the bolt in oppositely-inclined directions, 70 whereby on one movement of the carriage it will commence to cut the shingle from the thick end of the latter and on the next movement of the carriage will commence to cut the shingle from its thin end. By thus sawing 80 the shingles the entire bolt is utilized without waste.

As before described, each of the cross-bars 28 is made endwise adjustable on the arm 27, whereby the gage-block 33 may be adjusted 85 toward and from the plane of the saw, thus forming shingles of different thicknesses to be sawed. To compensate for such adjustment, the spring-pawls 39 and 40 are also made endwise adjustable in the manner described, so 90 that said pawls will engage the shoulders 37 and 38 on the disk 36.

As shown and heretofore described, the arm 51 is made endwise adjustable on its support, whereby the pendent arm of the trigger may 95 be caused to engage the cam at different periods in the travel of the carriage to release the arm 27, carrying the gage-block, at a sooner or later period of the travel of the carriage to accommodate the releasing mechanism to shingles of different lengths. 100

I have above described the gage-block 33 as being inclined on two of its sides only; but, as shown in Fig. 7 of the drawings, said gage-block may be alternately reversely inclined 105 on all four of its sides, as indicated at 34, 35, 36, and 37, and instead of alternately rocking the shaft 32 partially in one direction and then in the other the said shaft will be given a step-by-step rotation—that is to say, it will be 110 given quarter-turns successively in the same direction, so as to successively present said inclined sides to the plane of the saw. When the gage-block 33 is thus constructed, the disk 36 instead of being provided with but two 115 shoulders will be provided with four shoulders 64, and one of the pawls—as 40, for example—will be dispensed with, as shown in Fig. 8. Otherwise the operation of the device is the same as that before described, excepting that instead of partially rotating the gage-block in one direction and then in the other it will be given a continuous step-by-step rotation in one direction, as immediately 120 above explained.

I have shown and described herein a circular saw as being the preferred means for severing the shingles from the bolt; but it will be obvious to those skilled in the art that a band-saw may be substituted for the circular 125 130

saw, or other means for severing the shingles may be employed, the particular form of cutting mechanism forming no part of the present invention.

5 Having described my invention, what I claim is—

1. In a shingle-sawing machine, the combination with a saw and a carriage provided with a work-table, of a gage-block provided with 10 reversely-inclined flat sides and mounted to turn to bring said different sides into operative position, said gage being arranged to directly engage the work for the purpose specified.
- 15 2. In a shingle-sawing machine, the combination with a saw and a carriage provided with a work-table, of a gage-block provided with reversely-inclined flat sides and mounted to bring different sides into operative position, 20 said gage-block being arranged to directly engage the work, and a manually-operable means for turning the said different inclined sides into operative position one at a time for the purpose specified.
- 25 3. In a shingle-sawing machine, the combination with a saw and a carriage provided with a work-table, of a gage-block provided with reversely-inclined flat sides and mounted to turn to bring different sides into operative 30 position, said gage-block being arranged to directly engage the work and means for holding the gage-block in its different adjusted positions for the purpose specified.
- 35 4. In a shingle-sawing machine, the combination with a saw and a carriage provided with a work-table, of a gage-block provided with two reversely-inclined flat sides and mounted to turn to bring either of said sides into operative position, said gage-block being arranged to directly engage the work, for the 40 purpose specified.
- 45 5. In a shingle-sawing machine, the combination with a saw and a carriage provided with a work-table, of a gage-block provided with two reversely-inclined flat sides and mounted to turn to bring either of said sides into operative position, said gage-block being arranged to directly engage the work, and means for limiting the movement of the gage-block 50 in both directions and for holding it in its adjusted positions, for the purpose specified.
- 55 6. In a shingle-sawing machine, the combination with a saw and a carriage provided with a work-table, of a gage-block provided with reversely-inclined sides and mounted to turn to bring either of said sides into operative position, means for holding said block in its adjusted positions, substantially as described.
- 60 7. In a shingle-sawing machine, the combination with a saw and a carriage provided with a work-table, of a gage-block carried by the carriage and provided with reversely-inclined sides, said gage-block being mounted to turn to bring different sides into operative position to directly engage the work, and means

for adjusting the gage-block toward and from the plane of the saw, for the purpose specified.

8. In a shingle-sawing machine, the combination with a saw and a carriage provided with a work-table, of a gage-block carried by the carriage and provided with reversely-inclined sides, said gage-block being mounted to turn to present different sides and arranged to immediately and directly engage the work, and means for limiting the movement of the gage-block about its axis and for holding it in its different adjusted positions, substantially as described.

9. In a shingle-sawing machine the combination with a saw and a carriage provided with a work-table, of bearings movable with the carriage, a shaft journaled in said bearings, a gage-block mounted on the shaft and having reversely-inclined sides, and means whereby the shaft may be turned to bring said inclined sides, one at a time, into operative position, for the purpose specified.

10. In a shingle-sawing machine, the combination with a saw and a carriage provided with a work-table, bearings movable with the carriage, a shaft journaled in said bearings, a gage-block mounted on the shaft and having reversely-inclined flat sides, and arranged to directly engage the work, and means for arresting the movement of the shaft when any one of said inclined sides has been turned to operative position, substantially as described.

11. In a shingle-sawing machine the combination with a saw and a carriage provided with a work-table, of bearings movable with the carriage, a shaft journaled in said bearings, a gage-block mounted on the shaft and having two reversely-inclined sides, means for turning the shaft to alternately bring said inclined sides into operative position, a disk on the shaft provided on its periphery with two shoulders, and two fixed pawls for engaging said shoulders to limit the movement of the gage-block in both directions, for the purpose specified.

12. In a shingle-sawing machine the combination with a saw and a carriage provided with a work-table, of bearings movable with the carriage and adjustable toward and from the plane of the saw, a shaft journaled in said bearings, a gage-block mounted on the shaft and having two reversely-inclined sides, means for turning the shaft to alternately bring said inclined sides into operative position, a disk on the shaft provided on its periphery with two shoulders, and two fixed pawls for engaging said shoulders to limit the movement of the gage-block in both directions, for the purpose specified.

13. In a shingle-sawing machine, the combination with a saw and a carriage provided with a work-table, of a gage-block movable with the carriage and having reversely-inclined flat sides, said gage-block being mounted to turn to bring the different sides one at a time

immediately and directly in engagement with the work, means carried by the carriage for retaining the gage-block in its different adjusted positions, and means for automatically releasing the gage-block when a shingle is sawed to permit the latter to drop from the machine, substantially as described.

14. In a shingle-sawing machine, the combination with a saw and a carriage provided with a work-table, of a gage-block movable with the carriage and having reversely-inclined sides, said gage-block being mounted to turn to bring the different sides one at a time into immediate and direct engagement with the work, means carried by the carriage for retaining the gage-block in either of its adjusted positions, and means for automatically releasing and withdrawing the gage-block from operative position when a shingle is sawed, for the purpose specified.

15. In a shingle-sawing machine, the combination with a saw and a carriage provided with a work-table, of a gage-block movable with the carriage and having reversely-inclined sides, said gage-block being mounted to turn to bring either of said sides into immediate and direct engagement with the work, means for retaining the gage-block in either of its adjusted positions, means for automatically releasing and withdrawing the gage-block from operative position when a shingle is sawed, and means for automatically returning the gage-block to operative position, substantially as and for the purpose specified.

35. 16. In a shingle-sawing machine, the combination with a saw and a carriage provided with a work-table, of a swinging arm movable with the carriage, a gage-block carried by said swinging arm and having reversely-inclined sides arranged to immediately and directly engage the work, said gage-block being mounted to turn to present either of said inclined sides one at a time to the work, means carried by the carriage for retaining the swinging arm and gage-block in operative position, and means for automatically releasing and withdrawing said swinging arm from operative position when a shingle is sawed, for the purpose specified.

50. 17. In a shingle-sawing machine, the combination with a saw and a carriage provided with a work-table, of a swinging arm movable with the carriage, a gage-block carried by said swinging arm and having reversely-inclined sides, said gage-block being mounted to present either of said sides one at a time directly to the work, means carried by the carriage for retaining the swinging arm and gage-block in operative position, means for automatically releasing and withdrawing said swinging arm from operative position when a shingle is sawed, and means for automatically returning the swinging arm to operative position for the purpose specified.

65. 18. In a shingle-sawing machine the combi-

nation with a saw and a carriage provided with a work-table, of a swinging arm movable with the carriage, transverse bars adjustably mounted on the swinging arm, an axially-movable gage-block mounted in bearings in said bars and having reversely-inclined sides, means carried by the carriage for retaining the swinging arm and gage-block in operative position, and means for automatically releasing and withdrawing said swinging arm from operative position when the shingle is sawed, for the purpose specified.

19. In a shingle-sawing machine the combination with a saw and a carriage provided with a work-table, of a swinging arm movable with the carriage, transverse bars adjustably mounted on the swinging arm, an axially-movable gage-block mounted in bearings in said bars and having reversely-inclined sides, means carried by the carriage for retaining the swinging arm and gage-block in operative position, means for automatically releasing and withdrawing said swinging arm from operative position when a shingle is sawed, and means for returning the swinging arm to operative position when the carriage is retracted, for the purpose specified.

20. In a shingle-sawing machine the combination with a saw and a carriage provided with a work-table, of a swinging arm pivoted at one end to the carriage and freely movable at its other end on a support forming a part of the carriage, a gage-block carried by said swinging arm, a trigger pivoted to said support and arranged to engage at one end the free end of the swinging arm and hold the latter and the gage-block in operative position, a pendent arm fixed to the other end of the trigger, and a cam arranged to be engaged by the pendent arm when a shingle has been sawed to trip the trigger and release the swinging arm, for the purpose specified.

21. In a shingle-sawing machine the combination with a saw and a carriage provided with a work-table, of a swinging arm pivoted at one end to the carriage and freely movable at its other end on a support forming a part of the carriage, a spring for throwing the swinging arm out of operative position, a gage-block carried by said swinging arm, a trigger pivoted to said support and arranged to engage at one end the free end of the swinging arm and hold the latter and the gage-block in operative position, a pendent arm fixed to the other end of the trigger, and a cam arranged to be engaged by the pendent arm when a shingle has been sawed to trip the trigger and release the swinging arm, for the purpose specified.

22. In a shingle-sawing machine the combination with a saw and a carriage provided with a work-table, of a swinging arm pivoted at one end to the carriage and freely movable at its other end on a support forming a part of the carriage, a stop on said support for arresting the swinging movement of said arm, a gage-

block carried by the swinging arm, a trigger pivoted to said support and provided at one end with a shoulder arranged to engage the free end of the swinging arm and hold the latter and the swinging arm in operative position, a pendent arm fixed to the other end of the trigger, and a cam arranged to be engaged by the pendent arm when a shingle has been sawed to trip the trigger and release the swinging arm, for the purpose specified.

23. In a shingle-sawing machine the combination with a saw and a carriage provided with a work-table, of a swinging arm pivoted at one end to the carriage and freely movable at its other end on a support forming a part of the carriage, a spring for throwing the swinging arm out of operative position, a stop on said support for arresting the swinging movement of said arm, a gage-block carried by the swinging arm, a trigger pivoted to said support and provided at one end with a shoulder arranged to engage the free end of the swinging arm and hold the latter and the swinging arm in operative position, a spring for holding the shouldered end of the trigger in engagement with the swinging arm, a pendent arm fixed to the other end of the trigger, and a cam arranged to be engaged by the pendent arm when a shingle has been sawed to trip the trigger and release the swinging arm, for the purpose specified.

24. In a shingle-sawing machine the combination with a saw and a carriage provided with a work-table, of a swinging arm pivoted at one end to the carriage and freely movable at its other end on a support forming a part of the carriage, a stop on said support for arresting the swinging movement on said arm, a gage-block carried by the swinging arm, a trigger pivoted to said support and provided at one end with a shoulder arranged to engage the free end of the swinging arm and hold the latter and the swinging arm in operative position, a pendent arm fixed to the other side of the trigger, a cam arranged to be engaged by the pendent arm when a shingle has been sawed to trip the trigger and release the swinging arm, and means for adjusting the position of the cam to alter the time during the travel of the carriage at which it will be engaged by the trigger-arm, for the purpose specified.

25. In a shingle-sawing machine the combination with a saw and a carriage provided with a work-table, of a swinging arm pivoted at one end to the carriage and freely movable at its other end on a support forming a part of the carriage, a stop on said support for arresting the swinging movement of said arm, a gage-block carried by the swinging arm, a trigger pivoted to said support and provided at one end with a shoulder arranged to engage the free end of the swinging arm and hold the latter and the swinging arm in operative position, a pendent arm fixed to the

other end of the trigger, a cam arranged to be engaged by the pendent arm when a shingle has been sawed to trip the trigger and release the swinging arm, and means for limiting the movement of the carriage in both directions, substantially as described.

26. In a shingle-sawing machine, the combination with a saw and a carriage provided with a work-table, of a swinging arm pivoted at one end to the carriage and freely movable at its other end on a support forming a part of the carriage, a gage-block having reversely-inclined flat sides, said gage-block being mounted to turn in the swinging arm to present different sides in immediate and direct engagement with the work, means for throwing the swinging arm out of operative position when a shingle has been sawed, and a cam arranged to be engaged by a part carried by the swinging arm when the carriage is retracted for moving the swinging arm into operative position, substantially as described.

27. In a shingle-sawing machine, the combination with a saw and a carriage provided with a work-table, of a swinging arm pivoted at one end of the carriage and freely movable at its other end on a support forming a part of the carriage, a gage-block having reversely-inclined flat sides, said gage-block being mounted to turn in the swinging arm to bring different sides into immediate and direct engagement with the work, means for throwing the swinging arm out of operative position when a shingle has been sawed, and a curved cam arranged to be engaged by a part carried by the swinging arm when the carriage is retracted for moving the swinging arm into operative position, substantially as described.

28. In a shingle-sawing machine, the combination with a saw and a carriage provided with a work-table, of a swinging arm pivoted at one end to the carriage and freely movable at its other end on a support forming a part of the carriage, a gage-block provided with reversely-inclined flat sides and mounted to turn in said swinging arm to bring different sides into immediate and direct engagement with the work, means for throwing the swinging arm out of operative position when a shingle has been sawed, a roller carried by the swinging arm and a cam with which said roller contacts for moving the swinging arm into operative position when the carriage is retracted, substantially as described.

29. In a shingle-sawing machine, the combination with a saw and a carriage provided with a work-table, of a fixed support arranged alongside of the table for supporting the shingles being sawed, and a gage-block carried by the carriage and provided with reversely-inclined flat sides, said gage-block being mounted to turn to present different sides and arranged to immediately and directly engage the work, substantially as and for the purpose specified.

30. In a shingle-sawing machine the combination with a saw and a carriage provided with a work-table, a fixed support arranged along-side of the table for supporting the shingle being sawed and comprising a strip, one edge of which is in alinement with the saw, the end of said strip adjacent to the saw being beveled and overlapping the cutting edge of the saw, and a gage-block carried by the carriage

for alternately presenting the bolt at reverse angles to the saw, for the purpose specified.

In testimony whereof I have hereunto set my hand in presence of two subscribing witnesses.

JACKSON L. POSTON.
